UNITED STATES PATENT OFFICE.

ELMER L. SNYDER, OF SIOUX CITY, IOWA.

DESIGN FOR A LAMP SHADE.

Application filed March 26, 1923. Serial No. 5,594. Term of patent 3½ years.

To all whom it may concern:

Be it known that I, ELMER L. SNYDER, a citizen of the United States, residing at Sioux City, in the county of Woodbury and State of Iowa, have invented a new, original, and ornamental Design for Lamp Shades, of which the following is a specification, reference being had to the accompanying drawing, forming part thereof, of which—

Fig. 1 is a plan of my new and ornamental lamp shade design.

Fig. 2 is an elevation thereof, and

Fig. 3 is an inverted plan of the same.

I claim:

The ornamental design for a lamp shade, as shown.

ELMER L. SNYDER.
